AUTOMATIC GRAVE CURTAIN

Guy E. Smith, Mangum, Okla.

Application July 23, 1938, Serial No. 220,964

2 Claims.

(Cl. 27—30)

This invention comprehends certain new and useful improvements in undertakers' appliances or accessories, and relates particularly to an improved automatic grave curtain designed to close the top of an otherwise open grave preparatory to the committal services, so that an unbroken surface will be presented to the view of the funeral party as they approach the grave and thus avoid the harrowing sight which is so likely to affect the sensibilities and emotions of the funeral party as they assemble at the place of burial.

The principal object of the invention is a device of this character comprising a supporting mechanism or apparatus consisting of two complementary framework sections upon which an artificial grass mat is adapted to be placed, such supporting sections being initially in a horizontal position over or upon the mouth of the grave to support the mat in such a position as to give the appearance of unbroken turf, and the parts being so constructed and arranged that when the casket or vault is placed upon the lowering mechanism and the trip of the latter is released to permit the casket, for example, slowly to lower into the grave, the two sections of the framework will automatically and quickly swing downward against the side walls of the grave until the casket has been lowered to a predetermined degree or level, whereupon at a predetermined time, when the casket shall have passed below the then lower free sides of the framework sections, mechanism will be automatically put into operation to raise the sections again above the casket and against present the appearance of unbroken turf across the entire expanse of the otherwise open grave mouth.

With this and other objects in view, as will more fully appear as the description proceeds, the invention consists in certain constructions, arrangements and operations of the different parts as will be hereinafter more specifically described, reference being had to the accompanying drawings in which

Figure 1 is a top plan view of my automatic grave curtain, the lowering mechanism and the artificial grass mat being omitted for the sake of clearness;

Fig. 2 is a transverse sectional view, the section being taken substantially on the line 2—2 of Fig. 1, and showing the necessary parts of the casket lowering mechanism correlated to the present invention;

Fig. 3 is a fragmentary sectional view, the section being taken substantially on the line 3—3

of Fig. 1 but with the lowering mechanism also illustrated as in Fig. 2;

Fig. 4 is a sectional view substantially on the line 4—4 of Fig. 3.

Referring to the drawings, the numeral 10 designates four base blocks which are adapted to be positioned at the four corners of a grave opening designated generally 11, said base blocks being designed to support the casket or vault lowering mechanism hereinafter more specifically referred to and also to support the two complementary framework sections 12 upon which an artificial grass mat is intended to be laid for the purpose hereinbefore mentioned. As these two sections of the supporting framework of my automatic grave curtain are substantially identical in construction, a detailed description of one will manifestly suffice for both.

At its outer corners each framework section 12 is formed with sockets 13 designed to receive trunnions 14 which project inward from the base blocks 10, as best illustrated in Fig. 1, whereby the section 12 is pivotally mounted to swing from its outer edge about a horizontal axis and thus extend in a horizontal plane coincident with the plane of the mouth of the grave opening, as well as downward into a vertical position against the side wall of the grave, which last mentioned position is shown in Fig. 3 of the drawings.

The section 12, as clearly illustrated in Fig. 1, consists of an open or latticed framework made in two main parts which are adjustably connected together for longitudinal extension according to the length of the grave with which the device is associated, by means of rods 15 in one part telescoping into an adjacent part at the outer or axial edge thereof, the parts being held in adjusted position by means of set screws 16.

Each of the two parts of each section 12 is also formed with a transversely elongated opening 17 intermediate of its ends for a purpose shortly to be described, and in each of the openings 17 is a pair of gates 18 pivoted upon transversely extending rods 19 and provided with counterweights 20 tending to hold the gates closed or in the horizontal position indicated in Fig. 1. These openings 17 and the gates 18 that are pivotally mounted therein are coincident with the straps 21 of the casket lowering mechanism, as illustrated in Fig. 3, and the purpose and function of these gates will be hereinafter more specifically described in connection with the operation of the entire apparatus.

Coming now to the casket lowering mechanism,

only so much of which is shown as to illustrate an operative structure, 22 designates the rotating shafts around which the casket or vault supporting straps are adapted to be wound and to be unwound in the lowering operation, and in carrying out my invention I mount sleeves 23 upon the shafts 22, being preferably held thereon by means of set screws 24, said sleeves 23 being provided with flanges 25 to which cables 26 are connected 5 at one end, as for example, by means of hooks 27. At their relatively free ends the cables have connected to them weights 28 in order to keep them properly taut or under the requisite tension during operation, and immediately above their lower 10 or relatively free ends the cables 26 are provided with stops 29 designed to engage with eyes 30 thru which the cables pass, as clearly illustrated in Figs. 2, 3 and 4, the eyes 30 being connected to the end bars 31 of the frame sections 12.

Having thus described the construction and general arrangements of the parts of my improved automatic grave curtain, I shall now describe the operation of the device.

Initially and when ready for use, the frame sections 12 are pivotally mounted upon and between the base blocks 10 positioned at the corners of the otherwise open grave and a grass mat preferably formed in two equal sections and illustrated only in a conventional way, as at 32 in Fig. 2, is laid upon the frame sections 12 so as substantially to cover and close the otherwise open mouth of the grave and thus present what appears to be an unbroken expanse of turf when the funeral party and the casket or vault approach the grave for the interment.

Above the grass mat but manifestly not interfering with the view of it, is the open framework lowering mechanism, including the longitudinally extending shafts 22 with the supporting straps 21 wound thereon. When the casket, for example, is laid upon the straps 21 and the trip (not shown) of the conventional lowering mechanism is actuated, the straps 21, due to the weight of the casket, will unwind as the shafts 22 rotate, and in this initial movement of the casket from the dotted line position indicated by the reference numeral 33 in Fig. 2, to a point where the casket would otherwise contact with the grass mat upon the frame sections 12, the cables 26 will have unwound from the position illustrated in Fig. 2 to the extended position illustrated in Fig. 3 thus allowing the frame sections 12 quickly to move to their lowermost position flat against the side walls of the grave opening.

When, for example, the casket in its continued lowering movement, reaches the point indicated at A in Fig. 4, the continued rotative movement of the shafts 22 in the same direction will cause the cables 26 to commence to wind upon the sleeves 23 until the stops 29 come into contact with the eyes 30, but at that time the continued downward movement of the casket will have brought the latter to the plane indicated by B in Fig. 4, the top of the casket having passed free below or beyond the relatively free side edges of the frame sections 12, and at this time when the casket shall have effectively passed the then vertically disposed frame sections, the continued movement of the shafts 22 of the lowering mechanism and the accompanying continued winding of the cables 26 upon the sleeves 23 accompanied by the engagement of the stops 29 with the eyes 30, will cause the frame sections 12 to swing upwardly again until, when the casket has been completely lowered into the

grave, the frame sections 12, supporting the artificial grass mat or sections of mat, will have again assumed a completely horizontal position again closing the mouth of the grave and hiding the casket from view.

When the frame sections 12 move laterally downward, as hereinbefore described, obviously the gates 18 will not come into play, but when the frame sections are returned or are being returned to their uppermost positions, manifestly the gates 18 will yield in order to permit the straps 21, then in a substantially vertical position, to pass between them and when they have passed between them the counterweights 20 with which the gates are supplied, will automatically swing the gates 15 again to their normal horizontal positions.

It will be remembered that at the outset of the specification I mentioned that my improved automatic grave curtain was adapted for use in lowering not only caskets but vaults into a grave. 20 In connection with vaults, the outer corners of the frame sections 12 are formed with the openings 13 to receive the trunnions 14, but in connection with caskets a movement of less width is sufficient, and accordingly for use with caskets I form the end bars 31 of the frame sections 12 inward of the corners, with corresponding openings 13' for the reception of the trunnions 14, and in such event the base blocks 10 are, of course, moved nearer together and the eyes 30' are utilized instead of the eyes 30 that are spaced further apart. In other words, when a casket is being handled, the eyes that are nearer together and the pivot points that are nearer together are utilized, and the lowering mechanism is so arranged that the pair of cables 26 which position at that end of the framework shown to the right in Fig. 1, whereas if a vault is being handled, the eyes 30 (at the left hand in Fig. 1) and the outermost pivots are used, the lowering mechanism being turned end for end as these circumstances may require.

Preferably the outer and inner side edges or frame members of the frame sections 12 are provided with snap fasteners 12' for use with complementary fasteners in detachably connecting the sections of the artificial grass mat to the supporting framework.

From the foregoing description in connection with the accompanying drawings, it will be seen that I have provided a very simple, durable and efficient construction of automatic grave curtain which may be effectively used to shield or close the otherwise open mouth of a grave so that as hereinbefore mentioned, an apparently unbroken expanse of turf will be presented to the eyes of the funeral party approaching the place of burial with the vault or casket, and no open grave will be seen.

While the accompanying drawings illustrate what I believe to be the preferred embodiment of my invention, it is to be understood that the invention is not limited thereto and that various changes may be made in the construction, arrangements and proportions of the different parts 65 without departing from the scope of the invention as claimed.

I claim:

1. The combination with a casket lowering mechanism of the class described, including rotary shafts and casket or vault supporting straps adapted to wind upon said shafts, of pivoted covering frames extending from opposite sides over the mouth of a grave to be lowered thereinto, and counterweighted gates carried by said frames 75

in the vertical planes of said straps closing openings in the frames through which the straps pass.

2. The combination with a casket lowering mechanism of the class described, including rotary shafts and casket or vault supporting straps adapted to wind upon the shafts, of a pair of frames extending from opposite sides over the mouth of a grave, means pivotally supporting each frame at its ends for vertical movement on a horizontal axis extending along the outer side thereof whereby the frames may be lowered
- 5 into the grave, each of said frames having an opening extending transversely thereof and through its inner edge and adjacent each end for the passage of said supporting straps, a pair of gates in each opening, each gate being pivotally supported at a side of the opening whereby the two gates in each opening may be moved into the plane of the frame, and balance weights connected with the gates of each pair and functioning to maintain said gates in closed position 10 in the openings.

GUY E. SMITH.
